H. E. BILGER

FORM

Filed Feb. 9 1922

45 Inventor
Fig. 6 Harry E. Bilger
William Bradbury
McCall & Parker ~~Attys~~

UNITED STATES PATENT OFFICE.

HARRY E. BILGER, OF CHICAGO, ILLINOIS.

FORM.

Application filed February 9, 1922. Serial No. 535,202.

To all whom it may concern:

Be it known that I, HARRY E. BILGER, a citizen of the United States, and resident of Chicago, in the county of Cook and State of Illinois, have invented a certain new and useful Improvement in Forms, of which the following is a full, clear, concise, and exact description, reference being had to the accompanying drawings, forming a part of 10 this specification.

This invention relates to forms such as used in constructing culverts, bridges, sewers and the like, of concrete or similar material.

15 The object of the invention is the provision of a form structure, the parts of which may, without modification, be employed to produce forms of varying sizes and proportions with a minimum amount of labor.

20 A further object is the provision of a form of this character in which there will be no large parts which will be difficult to handle, and no small parts which are likely to get lost, it being the object of the present invention to provide a form which may be 25 readily erected by one man.

One feature of the invention is the manner of constructing the form centers or supports of a plurality of interchangeable sections, thus permitting the same sections to be 30 used without modification in the construction of forms of varying sizes and proportions.

Another feature is the construction of the 35 center or support sections so they may be used on either side of the form, thus avoiding right hand and left hand parts, and rendering the support sections completely interchangeable.

40 Another feature of the invention resides in the manner of forming reinforcing flanges for the edges of the cover plates, and also in the manner of arranging the flanges to form with the surface of the plate an angle 45 of somewhat less than 90° so that the side edges of the cover plates will closely engage at a point adjacent to the surface of the cover plates thus avoiding the formation of projecting portions of concrete on the inner surface of the completed culvert or bridge.

50 Another feature is the structure which permits the same cover plates to be used on either side or the top of the form, without modification.

In the drawing,

55

Figure 1 is an end view of applicant's form complete;

Figure 2 is a view at right angles to Figure 1 of one of the center uprights or supports with the cover plates attached thereto;

60

Figure 3 is a perspective view of one end of one of the cover plates;

Figure 4 is a bottom view of the lowermost section of a center upright, showing the plate attached to the lowermost section 65 which is arranged to maintain the lower edge of the lowermost cover plate in alignment with the upper cover plates;

Figure 5 is a view of the adjacent portions of two of the center upright sections, 70 showing a modified manner of joining the sections;

Figure 6 is a section on the line 6—6 of Figure 5;

Figure 7 is a view similar to Figure 5, 75 but showing a still further modified form; and

Figure 8 is a section on the line 8—8 of Figure 7.

Referring now to the drawings, in which the same reference characters indicate like parts in the several views, each of the center uprights consists of a plurality of sections of I-beams, stacked each upon the others, with the surface of their flanges in engagement. These sections will preferably be of six-inch I-beams, about four inches in length, although other sizes and proportions may be employed. Each upright consists of a lower section 10, and an upper section 11; also where the culvert is to have an inside height of more than one and one-half feet, each upright will comprise one or more center upright sections 12. Sections 10, 11 and 12 are substantially identical in construction, except that to the lower flange of each lower section 10 is secured, by rivets 13 or in any desired manner, a plate 14, and to the upper flange of the upper sections is secured a pair of angles 15, so disposed as to form a supporting channel or saddle for the two-by-fours 16, which support the top cover plates 17.

To each of the center upright sections 10, 11 and 12 are secured by means of the rivets 18, the shanks 19 which extend outwardly and upwardly and terminate in the hooks 20. The hooks 20 of each section are spaced

apart and extend substantially parallel to each other, and also parallel to the web of the upright sections.

The upper flange of each of the upright sections, except the upper section 11, is provided with openings 21 and 22. These openings are provided adjacent to the diagonally opposite corners. Referring to Figure 1, the opening 21 is in the left hand near corner, while the opening 22 is adjacent to the right hand far corner. The bottom flange of each of the sections, except the lower section 10, is provided with projecting lugs 23 and 24, which are rigidly secured in the flange as by welding. The projecting portions of these lugs are arranged to engage and enter the openings 21 and 22 in the upper flange of the adjacent section. Thus, lateral displacement of one section in relation to the other is prevented by means of the lugs 23 and 24 entering the openings 21 and 22 respectively.

The side cover plates 25 are identical in construction with the top cover plates 17. The corner cover plates 26, however, are different, as will presently appear. Each of the side cover plates 25 and top cover plates 17 consists of a sheet of metal 27 provided at each edge thereof with a flange 28. The flanges 28 are each provided adjacent to each end with an opening 29, which is slightly greater in diameter than the hooks 20. While only one end of the cover plate is shown in Figure 3, it is to be understood that the opposite end will be in all respects symmetrical with the end shown.

As previously stated, the upright sections are made of six-inch I-beams. The cover plates 25 and 17 are six inches in width, over all, i. e., the cover plates correspond in width with the height of the upright sections. Each of the flanges 28 consists of a re-bent portion of the metal forming the plate. In practice, the flange is preferably formed by folding the edge of the plate back upon itself and then folding the double portion so as to produce a flange which forms an angle of slightly less than 90° with the face of the plate. The flanges 28 are arranged at an angle less than 90° with respect to the plate in order that their edges may closely engage at a point adjacent to the surface of the plate, thus preventing the formation of undesirable projecting portions of the concrete or cement at the points where the plates join. The re-bent structure of the flanges not only strengthens the plates, but also makes them much more convenient for handling, as the sharp, side edges are thus eliminated.

The corner cover plates 26 consist of two sections extending at right angles to each other, being six inches in width each way. Each of the folded edges of the corner plate sections is provided with a perforated

flange which is, in all respects, similar to the flange 28 of Figure 3.

With the form sections herein disclosed, forms of varying sizes in multiples of six inches may be provided. All that is necessary is to add or to take from the sections of the supports, and cover plates.

The supporting two-by-fours 16 are preferably shouldered as indicated at 30, to properly space the upper ends of the center uprights. The distance between the shoulders 30 will always be a multiple of six inches.

Each of the upright sections 10, 11 and 12 is preferably substantially four inches in length. The end of the plate 14, however, secured to the bottom flange of the lower section 10 projects outwardly substantially two inches, so as to engage the inner surface of the lower side cover plate to maintain it in alignment with the cover plates above. The angle members 15, which comprise the saddle for the timbers 16, also project nearly two inches beyond the flange of the upper section 11 to which they are secured. Preferably, the angles 15 will not extend quite two inches beyond the uprights, as it is desirable to leave a slight amount of play in order to insure that the lateral edges of the top cover plates may be brought firmly into engagement. While the cover plates may be of any desired length, it has been found practical to make these substantially four feet in length.

The lowermost upright sections 10 are supported on a two-by-four wood timber 32. The blocks 33 are nailed to the two-by-four 32 at the inner edges of the uprights, in order to maintain the uprights in spaced relation. The distance between the remote edges of the blocks 33 will in all instances be a multiple of six inches.

The webs of the uppermost upright sections 11 are each provided with a perforation 34, which is engaged by a hook 35 at the end of the chain 36. The chain 36, adjacent to its opposite end, is secured to the two-by-four 32 by means of a nail passing through one of the links and into the timber 32. If desired, instead of an integral timber 32 being employed, four inch sections may be arranged under each of the uprights, and the intervening space be filled in by six-inch sections, or twelve-inch and six-inch sections, as desired. This arrangement obviates the necessity of providing a different base timber for each different width of culvert or bridge constructed. The top supporting members 16, however, will consist of integral two-by-four or two-by-six timbers.

Assuming that the excavation has been made, and that the usual concrete base 37 has been placed and permitted to set, the present form will be set up as follows:

Two-by-four timbers, as 32, will be arranged transversely of the culvert at intervals of four feet. These timbers will, of course, be parallel to each other, and at right angles to the axis of the completed form. One of the lowermost upright sections 10 will then be placed on the end of the first two-by-four, and a side cover plate will be positioned with its upper end perforation 29 in engagement with the hook 20, as indicated in Figure 1. A lower upright section 10 will then be placed on the next timber 32, and the perforation 29 at the opposite end of the cover plate will be caused to engage the near hook on the next upright section. Also, another cover plate will have the perforation in its upper flange engaged with the far hook on the second upright section, and so on, until the required length of the culvert or bridge has been reached. It will be understood, of course, that the timbers 32 will be properly proportioned prior to inserting them under the upright support section. Additional support sections 12 will then be placed upon the lowermost sections 10 with the pins 23 engaging the openings 21 and 22 in the respective flanges. The next cover plate will then be arranged so that the perforation 29 in its lower flange engages a hook on the lowermost section 10, while the perforation 29 in its upper flange engages the hook on the second section 12. Thus, the sections will be built up, each on top of the others, until the uppermost supporting sections 11 are reached. When the sections 11 are in place, the supporting timbers 16 will be placed in the saddles formed by the brackets 15—15, as indicated in Figure 1. Then the corner cover plate sections 26 will be placed in position with the perforation in the lower flange engaging the hook of the upper section 11, while the flange of the horizontal portion of the corner cover plate will engage behind the corner of the angles 15, thus maintaining the corner cover plate in position. The space between the inner edges of the corner cover plate will be filled in by merely placing the top section 17 therebetween. If desired, pins 38 may be inserted through the aligned openings in the adjacent flanges in the top cover plates in order to assist in maintaining the sections in alignment. Due to the appropriate spacing of the hooks 20, and the openings 29 in the flanges of the side cover plates, the adjacent end edges of the cover plates are maintained in close engagement. Due to the fact that the flanges 28 are turned so as to lie at an angle slightly less than a right angle with the surface of the plate, the edges of the several cover plates are caused to engage practically at the surface thereof, thus avoiding leakage of the concrete between the plates and preventing the formation of projecting portions

on the inner side of the concrete structure. This structure also avoids the tendency to spread the plates, due to the entrance of concrete between the flanges of the plates.

The lower edges of the lower side cover plates will be in engagement with the base 37, and all the other side cover plate sections will be supported on the lowermost sections as the cover plates only loosely engage the hooks 20. As previously explained, the lower edge of the lowermost cover plate is maintained in alignment with the other cover plates by means of the plates 14. A slight clearance, however, is provided between the angle 15 and the corner plate 26, in order that the pressure brought to bear on the plates 26 when the concrete or cement is poured in place at the sides will cause a close engagement of the lateral edges of all of the cover plates. If desired, the upper ends of the uprights may be prevented from separating by driving nails through the openings 39 in the angles 15 and into the supporting timber 16. After the form is in position, when the height of the form requires, the chains 36 will be applied with the hooks 35 engaged in the openings 34, the chains being drawn taut and the opposite ends being secured to the base timber 32, as by means of nails 40. These chains provide a diagonal bracing to maintain the form true. Small nails may be driven into the base timber 32 through the notches 41 to assist in maintaining the parts in position.

It will be noted that the form shown in Figure 1 provides for a culvert or bridge having an opening therethrough of exactly two feet in height, and two feet in width, and that notwithstanding the fact that the form is shown as in place, a substantial opening is provided through the center of the form to permit the discharge of water in case of floods or other unexpected flow, while the form is in place.

Assuming that the concrete has been placed about the form, and has hardened, all that is necessary to release the form so as to permit its ready removal is to knock the timbers 32 out from under the flanges of the lowermost sections 10. This may be done by a maul, axe, bar, or with any other desired instrument. As soon as the timber 32 has been knocked out from under the lowermost sections, the upright sections 10, 12 and 11 will fall, causing the hooks 20 to disengage the openings 29 in the side cover plates. The complete uprights may be moved toward each other at their lower ends, so as to completely disengage them from the rest of the form. The various sections of the form may now be readily removed from the culvert or bridge, section by section, by a single man, as none of the sections is of excessive weight or size.

It is obvious that many different propor-

tions of forms may be provided with the elements of applicant's form. Taking merely the sections illustrated in Figure 1, all possible combinations of length and width in increments of six inches up to two feet may be provided. Thus, twelve different proportions of forms may be produced from the sections shown in Figure 1 with the exception that different top supports 16 will have 10 to be provided for each different width of form.

By providing four additional center upright sections 12 for each side upright, and providing twelve additional cover plate sections for each four feet in length, a form four by four feet may be constructed. Again, the various sections of the four by four foot form may be used to create forms of varying sizes in increments of six inches. 15 Considering merely the sections necessary to make a four by four foot form, it will be seen that not less than ninety different proportions of forms may be made by using these sections, and in each case except where 20 the smallest sizes of forms are produced, a substantial opening will be provided through the center of the form to take care of any flow of water which may occur.

In the larger sizes of forms, it sometimes 30 happens that the inward side-thrust of the concrete causes a bulging of the form inwardly, due to the fact that the lugs 23 and 24 of the form shown in Figures 1 and 2 merely loosely engage in the openings 21 35 and 22 of the flange below. In order that the upright sections may be comparatively rigidly secured together, the modifications shown in Figures 5 to 8 inclusive have been provided.

40 Referring first to the modification shown in Figures 5 and 6, the lowermost flange 42 of the two engaging flanges is provided adjacent to one edge thereof with an upwardly extending headed lug 43. The lowermost flange 44 of the upper section is provided 45 with a notch or slot 45, arranged to receive the lug 43, as indicated in Figure 6. The corner of the flange 44 diagonally opposite to the slot 45 is provided with a downwardly extending headed lug 46, which is arranged 50 to be received in a slot 47 correspondingly formed in the flange 42. Thus, it will be seen that the lugs 43 and 46 may be caused 55 to engage their respective notches or slots 45 and 47 by a slight sidewise movement of the section, one with respect to the other. As the heads of the lugs 43 and 46 are slightly slanted on their inner surfaces, and as the flanges 42 and 44 are slightly tapered, the 60 lugs 43 and 46 are caused to engage the flanges with a wedging action, and thus firmly lock the sections together. The sections may be readily loosened, one from the other, by a slight blow on either section in 65 the appropriate direction. In some in-

stances, it may be found desirable or necessary to provide merely a single lug, as 43, and notch 45, but where a single lug and notch is provided it should be arranged at the edge of the supporting section which is 70 remote from the hooks.

In Figures 7 and 8, another manner of securing the upright sections together is disclosed. The lower flange of the two engaging flanges is provided with a pair of upwardly extending headed lugs 48, which may be similar to the lugs 43 and 46 of Figure 6. The lower flange of the upper one of the two adjacent sections will be provided with the keyhole slots 49. It will be understood 75 that the lugs 48 and slots 49 will be correspondingly positioned at the diagonally opposite corners of the plates. In securing the sections together, the upper plate would be placed on the lower one, so that the heads 80 of the lugs 48 would pass upwardly through the large portions of the slots 49. The upright sections will then be moved, one relatively to the other, so as to position the reduced portions of the lugs 48 in the reduced 85 portions of the keyhole slots 49, thus locking the two sections together. If desired, the keyhole slots may be placed in the lower of the two engaging plates, and the 90 lugs caused to project downwardly from the upper of the two engaging plates.

Another expedient which may be employed is to provide aligned openings in the base flanges of the sections shown in Figures 1 and 2 and when the sections are used 100 to produce a form of large size, where bulging is apt to occur, a bolt may be inserted through these aligned openings in order to prevent the inner edges of the adjoining base flanges from spreading. Other expedients 105 for preventing the separation of the adjoining flanges of the upright sections are contemplated by applicant, but they will not be herein specifically noted.

While the drawings and the above description have been limited to the disclosure of certain definite details, it is to be understood that applicant contemplates various modifications in the details of his invention.

While six-inch I-beams have been shown 110 as the material from which the upright center sections have been formed, it is readily conceivable that these sections may be made of other materials, or other forms of structural steel. The dimensions of the various parts of applicant's form may also be varied. It is therefore to be understood that the invention is to be limited merely by the scope 115 of the appended claims.

What I claim is new and desire to secure 120 by Letters Patent of the United States is:

1. In a form, support, and cover plates mounted thereon, each of said supports consisting of a plurality of sections of I-beams, one of the flanges of the I-beams being pro- 125

vided with an opening, and the adjacent flange of the next section being provided with a correspondingly positioned lug adapted to project into said opening.

5 2. In a form, a plurality of upright supports, each comprising a plurality of like sections of I-beams, the adjacent flanges of said sections being provided with openings, and lugs arranged to be received by said

10 openings.

3. In a form, a plurality of upright supports, each comprising a plurality of like sections, a hook projecting outwardly from each of said sections, and side cover plates 15 having inwardly extending flanges provided with openings arranged to receive said hooks respectively.

4. In a form, a plurality of upright supports, each comprising a plurality of like 20 sections of I-beams, hooks projecting outwardly from the web of each of said sections respectively, and side cover plates having inwardly extending flanges provided with openings arranged to receive said hooks 25 respectively.

5. In a form, a plurality of upright supports, each comprising a plurality of like sections of I-beams arranged with their webs in alignment and flanges in abutting relation, hooks, one projecting outwardly from 30 each side of the web of each of said sections, and side cover plates arranged in endwise abutting relation and having flanges provided with openings arranged to receive said 35 hooks respectively.

6. In a form, a plurality of upright supports, each comprising a plurality of sections, a hook projecting outwardly from each of said sections, and side cover plates, 40 each having inturned flanges provided with openings arranged to receive the hooks of adjacent sections of said supports, respectively.

7. In a form, a plurality of upright supports, each comprising a plurality of like 45

sections, a hook projecting outwardly from each of said sections, side cover plates having inturned flanges provided with openings arranged to receive said hooks respectively, and means for supporting said supports, 50 said means for supporting being capable of removal to permit said support sections to move downwardly to disengage said hooks from said openings.

8. In a form, a plurality of upright supports, each comprising a plurality of like sections of I-beams arranged with their flanges in abutting relation, hooks projecting outwardly from the web of each section, side cover plates having flanges provided 60 with openings arranged to receive said hooks, and means for permitting said supports to move downwardly to disengage said hooks from said openings.

9. In a form, a plurality of upright supports each comprising a plurality of like sections, each section consisting of a web with a flange at each edge thereof, side cover plates having flanges, means joining said cover plate flanges to said sections respectively, and means for supporting said supports, said means for supporting being capable of removal to permit said sections to move downwardly and render said joining means inoperative. 70

10. In a form, supports, metal cover plates on said supports with their edges in abutting relation, flanges at the opposite edges of each plate, each of said flanges consisting of a portion of the plate re-bent on itself with the outer side thereof positioned at an angle of slightly less than 90° to the plane of the plate. 80

In witness whereof, I hereunto subscribe my name this 6th day of February, 1922.

HARRY E. BILGER.
